UNITED STATES PATENT OFFICE.

WILLIAM C. TREGONING, OF CLEVELAND, OHIO.

ELECTRICAL ATTACHMENT-PLUG.

1,176,622.

Specification of Letters Patent. Patented Mar. 21, 1916.

Application filed December 21, 1914. Serial No. 878,259.

To all whom it may concern:

Be it known that I, WILLIAM C. TREGONING, a citizen of the United States, residing at Cleveland, in the county of Cuyahoga and State of Ohio, have invented certain new and useful Improvements in Electrical Attachment-Plugs, of which the following is a specification.

This invention relates to an electrical attachment plug, and the invention comprises an attachment plug particularly constructed to receive a pair of conducting wires at the rear end and to project jointly through the front end of the plug body for convenient attachment to a pair of binding screws located in visible and accessible places at the front end of said plug without requiring removal of the screw shell from the main body of the plug, regardless of whether the plug is of the fixed sleeve type or the revolvable sleeve type, and the construction of the plug also involves the use of a rotatable crown located at the front end of the plug to grip both conducting wires to relieve the binding screws of all pulling strains and which crown member is especially designed to carry the end contact for the plug and to permit final attachment of one wire conductor to said contact to effect locking of said crown member against a return rotation subsequent to gripping the conducting wires by said crown member.

In the accompanying drawings, Figures 1 to 9 show one form of an attachment plug with a revolvable sleeve, constructed according to my invention, Fig. 1 being a perspective view of a complete plug as it appears with the conducting wires attached. Fig. 2 is a perspective view of the wire-gripping crown member and the end contact screw and washer assembled. Fig. 4 is a side view of the main parts of the plug sleeved upon a cable or cord having two electric conductors stripped therefrom and extending through the outer end of the plug body in position for attachment to the terminal binding screws. Fig. 5 is a perspective view of the inseparable parts of the plug. Fig. 6 is a central section longitudinally of the plug with the conductors at-

tached to the binding screws and gripped by the crown member. Fig. 7 is a plan view of the conducting ring for the screw shell. Fig. 8 is a bottom view of Fig. 4. Fig. 9 is a central section longitudinally of the plug without the crown member and showing a view at right angles to Fig. 6. Fig. 10 is a sectional view of a modified form of the invention and Fig. 11 is a plan view and transverse section on line 1—1, Fig. 10. Fig. 12 is a sectional view of the screw shell and its contact ring affixed together in inseparable and rotatable relations by projections on the ring. Fig. 13 is a part elevation and part sectional view of a solid plug embodying my invention. Fig. 14 is an end view, and Fig. 15 a transverse section of the solid plug shown in Fig. 13.

In my improved electrical attachment plug, the wiring thereof, that is, the fastening of the electric conductors or wires to the plug terminals is an operation which is greatly simplified and made as convenient as possible. In this way, time and labor are saved. Accordingly, I make the attachment plug in two main parts—a body 2 having a screw-shell 3 inseparably affixed thereto, and a crown member 4 having a screw stem 5 separably engaged with said body. Further, I locate both terminals or binding screws 6 and 7 for the wires 8 and 9, respectively, at the front ends of said body 2 and crown 4, respectively, and provide a through opening 10 centrally of the body 2 to permit both wires 8 and 9 to be inserted freely therein and projected to any desired distance beyond the front end of said body, especially when the crown 4 is removed, see Fig. 4. Stripping of the wire ends of their insulated covering may proceed either before the wires are inserted or after sleeved relations are established, and then one wire end 12 may be attached to the binding screw 6 which is visible and directly accessible at the front end of body 2 immediately adjacent the central opening 10. Binding screw 6 is carried by the screw shell 3, either directly or indirectly; that is to say, in a plug having a screw shell which does not rotate independently of the body 2, I prefer to mount said screw 6 on an integral or affixed ear 14 at the front end of said shell, see Fig. 13, and in a plug having a revolvable screw shell, such as

shown in Figs. 6 and 10, I prefer to mount said screw 6 on a separate electric-current-conducting ring 15 mounted upon and carried by said shell, see Fig. 12. It must be understood that crown 4 is not in place when end 12 of wire 8 is anchored by screw 6, and that the body 2 and its attached shell are inseparable and held together in one hand while the other hand is free to affix the wire 10 end 12 underneath the head of screw 6 by means of a screw driver or other suitable tool. The stripped end 16 of the second wire 9 is bent laterally out of the way during the foregoing operations, see Fig. 13, and the 15 crown 4 is then screwed into place before attaching said end 16 to the second terminal or binding screw 7 at the center and front of the crown.

One function of crown 4 is to carry the 20 end contact for the plug consisting of the screw 7 and brass washer 17, and another function of the crown is to cover and protect the first binding screw 6 and the wire end 12. A further and important function 25 of the crown is to grip or wedge both wires 6 and 7 within the body 2 to relieve all pulling strains on the terminals or binding screws, and such gripping or wedging is effected by screwing the stem 5 into the 30 screw-threaded front portion 18 of the central opening 10 until both wires are engaged by the conical or rounded end 19 of the stem and pressed tightly against the sharp-edged shoulders 20 at opposite sides of opening 10 35 at the base or inner end of the two opposite channels or grooves 21 and 22, one for each wire 8 and 9 respectively. Said channels extend to and are open at the front end of body 2 which permits the wires to be spread 40 apart and to extend through the body at opposite sides of the screw stem 5. When the stem is in place, it prevents short circuiting of the two bare wire ends as both body 2 and the crown 4 and its stem are 45 made of insulating material. The size of the channels in transverse section is merely sufficient to admit the wires freely and to prevent twisting or displacement of the wires when the screw stem 5 rotatably engages and wedges the wires against the 50 shoulders 20. The unthreaded portion of the opening 10 is slightly larger in diameter than the front threaded portion 18 to accommodate the larger diameter of such wires 55 as have additional insulation or covering 23. The necessity of rotating crown 4 to effect wedging and gripping of the wires demands that the wire end 16 of the second wire 9 be projected laterally as shown in Fig. 13, and the fastening of the wire end 16 to the end contact or screw 7 subsequent to such rotation of the crown requires a longitudinal groove or slot 24 in the periphery of the 60 crown.

65 Different thicknesses of wire or insulating

covering affect the final setting of the crown relatively to the front end of the body, but a plural number of radial slots 24 in the crown enable the operator to produce maximum wedging results on the wires regardless of their thickness and at the same time place one of the slots opposite and in parallel alinement with the open end of channel 22 so that the wire end 16 may be drawn inward toward the center of the crown and wound around screw 7 within the central depression 25 beneath washer 17. The result is that the bare wire end 16 is retired and protected and when anchored in place by tightening screw 7 the crown is also locked 80 against return rotation by the taut wire lodged in the slot and spanning the slight gap between the crown and body. The radial slots 24 also provide a good gripping edge to rotate the crown and present a very 85 ornamental and distinctive appearance to the plug as a whole, see Fig. 14. A small cylindrical core 26 of metal is molded centrally in the crown at the base of the depression 25 to receive screw 7 and to provide 90 good electrical contact for the wire end 16, see Fig. 6.

In Figs. 1 to 9, I show a plug having a screw shell rotatably mounted on a body which is reduced in diameter at its rear end 95 27 and inclosed by a sleeve 28 of insulating material having external grooves 29 engaged by inwardly-bent tongues 30 on the screw shell 3. The front end of the screw shell has an inturned flange 31 overlapping an 100 annular shoulder 32 on the body and the shell is free to rotate upon the body but is held inseparable therefrom by said flange and the hand-gripping sleeve engaged by tongues 30. The contact ring 15 in this 105 form of plug surmounts the flange 31 and is fastened to the front end of the body by pins 32, see Fig. 9 or their equivalent, and the annular edge 33 of the contact ring is knurled to afford a good finger gripping 110 surface which is utilized to hold the ring from turning when the binding screw 6 is rotated in fastening the wire end 12 to the ring.

In Figs. 10 and 11, I show a plug having 115 a rotatable screw-shell secured upon a tubular mounting or sleeve 34 of insulating material by an inwardly-projecting flange 35 of double thickness and by crimping or indenting part of the shell at 36 into one or more recesses 37 in the side of the sleeve. The contact ring 15 is carried by the flange 35 and is rotatably and permanently affixed to the shell by an inturned flange 38 at the front end of the shell. The plug body 2, 120 contact 15, and the sleeve 34 and screw shell 3 are inseparably united together to provide a single unit for greater convenience in handling the parts during wiring operations, but to facilitate wiring operations the rear 130

end 39 of the body shown in Fig. 10 is extended beyond the sleeve 34 and serrated to afford a finger grip in holding the body while attaching the wire end 12 to the binding screw 6. Or extension 39 may be omitted, and the front end of the sheet cut away in part on opposite sides to expose the annular edge of the contact ring 15 to provide a finger grip, see Fig. 11. In Fig. 12, 5 I show a screw-shell with an inturned flange 40 at its front end inseparably affixed to a metal contact ring 15 by downwardly and outwardly extending ears or projections 42. The shell is free to rotate but is held in permanent contacting relations with the ring by said ears or projections and the annular edge 43 of the ring affords a finger grip. 10 In Figs. 13 to 15, I show a plug in which the screw shell is immovably fixed to the body by pointed indents 44, but the shell 15 may be molded on the body or any other suitable means of attachment may be used instead.

The beveled or conical end of the screw 25 stem 5 serves to spread the wires apart before gripping or wedging occurs and the wedging action is also in the same direction, that is, laterally, which avoids severe pulling strains on the wire and their binding 30 ends.

What I claim is:

1. An attachment plug for electric wires comprising independent contact members having terminals for the wires, a body part 35 and a rotatable non-conducting screw member at the front end thereof to support said members, and seats internally of the body and a wedging portion on said screw member to grip the leading-in wires and relieve 40 said terminals of pulling strains.

2. An attachment plug for electric wires comprising independent contacts and binding screws, a supporting body for one of said contacts having wedging surfaces for 45 the leading-in wires, and a rotatable finger-grip member having an extension of insulating material projected into the front end of the body to grip the wires and relieve the binding screws of pulling strains, said member carrying one of said contacts and binding 50 screws at the front end thereof.

3. An attachment plug body for electric wires having independent contacts and binding screws mounted thereon and internal 55 seats for the leading-in wires, the mounting for one of said contacts comprising a crown having a screw stem of insulating material engaged with the front end of the body and to wedge the wires upon said seats and relieve 60 the binding screws of pulling strains.

4. An attachment plug body for electric wires having independent contact members supported thereon and provided with internal 65 seats for the leading-in wires, and a crown member at the front end of said body

having a screw stem with a conical end to engage and wedge the wires against the seats within the body.

5. An attachment plug for electric wires comprising a body having internal wedging 70 surfaces for the wires and provided with a contact shell connected with one of said wires, and a non-conducting screw member having an end contact for one wire and an integral stem to wedge the wires against 75 said surface.

6. An electrical attachment plug comprising an open body having a screw shell, a rotatable crown of insulating material at the front end of said body having an integral 80 screw portion in direct screw engagement with said body and carrying an end contact, and terminal binding screws for conducting wires at the front of said shell and crown, respectively. 85

7. An electrical attachment plug, comprising a screw-shell having a terminal binding screw, a mounting for said shell having an opening for the leading-in wires, and a crown member in rotatable screw engagement with said mounting provided with a contact and wire fastening screw at its front end and a radial slot in its outer edge open to said contact screw to accommodate a wire conductor and facilitate wiring operations 95 and to effect locking of said crown against rotation by means of said wire conductor. 90

8. An attachment plug for electric wires comprising a body having a contact member thereon provided with a terminal connector for a conducting wire and wedging seats within for said wire and a second wire, and a rotatable crown having screw engagement with said body and provided with an end contact and terminal connection for the 100 second conducting wire and adapted to wedge both wires within the body at the end of its rotative movement in respect to said body. 105

9. An attachment plug for electric wires 110 comprising a body having a screw shell inseparably affixed thereto, and a crown member having an integral screw stem of insulating material separably and rotatably engaged with the front end of said body. 115

10. An attachment plug for electric wires comprising a body having a central opening with wedging surfaces for the wires, a screw shell mounted on said body, a crown member having a screw stem engaged within said body opening in wire-wedging relations with said wedging surfaces, and an end contact and terminal connection at the front of said crown for one of the wires. 120

11. An attachment plug for electric wires 125 comprising a body having a screw-threaded opening at its front end and wire-wedging surfaces internally, and provided with a screw-shell and a wire-connecting terminal 130 at the front end thereof, in combination

- with a crown member having a screw stem engaged with said body adjacent said wire-wedging surfaces and provided with a contact and wire-connecting terminal at its front end.
12. An attachment plug for electric wires, comprising a body having a central screw-threaded opening and longitudinal passages open at each side thereof and at the front 10 end of said body for the leading-in wires, a screw shell and wire-connecting means therefor mounted on said body, a crown member having a screw stem engaged within said opening between said passages to wedge the leading-in wires against the interior walls of the body, and a contact and wire terminal connection at the front end of said crown member.
13. An attachment plug for electric wires comprising a body having a central screw-threaded opening, and a rotatable crown of insulating material adapted to screw into said opening from the front end of said body, a screw shell for said body, and terminal binding screws for the electrical wires mounted at the front ends of said body and crown, respectively.
14. An attachment plug for electric wires comprising a body having a central opening with shouldered side channels and screw-threads and provided with a screw shell and a wire-connecting terminal for the shell, in combination with a slotted crown having a screw stem to screw-engage said body and 35 to co-operate with the channel shoulders to grip the wires and provided with a contact and wire-connecting terminal at its front end.
15. In an attachment plug for electric wires, a body and a screw shell mounted thereon, and a wire connection for said shell, said body having passages for the leading-in wires, in combination with a screw crown separably engaged with said body and having a central end contact and 45 radial slots in the periphery thereof to align with one of said passages for the wire leading to said contact.
16. In an attachment plug for electric wires, in combination, a body having a central passage for the wires and an outer screw shell, a non-conducting crown member having rotatable screw engagement with said body and provided with a peripheral slot and an end contact, and leading-in wires 55 extending through said central passage and slot connected with said shell and end contact.
17. An attachment plug for electric wires having a body with a screw shell inseparably affixed thereto and a wire binding screw for said shell, said body having a central opening and wedging seats for the wires, in combination with a crown member having a slot in its edge and provided with a screw stem to enter said central opening to
- grip the wires and having an end contact and binding screw for one of the wires.
18. In an attachment plug for electric wires, a body of insulating material having a central screw portion and channels at each 70 side thereof open to the front end of the body, a screw shell mounted on said body, wire-connecting means at the front end of said body for said shell, and a screw crown removably engaged with said body and having a central end contact and wire-binding screw and provided with an edge slot to accommodate a conducting wire for the end contact.
19. In an attachment plug for electric 80 wires, a body having a contact ring and a wire binding screw at its front end and carrying a rotatable screw shell, a separate rotatable crown in screw engagement with said body, and a front end contact and a wire 85 binding screw upon said crown.
20. In an attachment plug for electric wires, a body having a central opening and gripping surfaces for the wires and provided with a screw-threaded portion at its 90 front end, a screw shell rotatably mounted upon said body, a contact ring at the front end of said body to hold the shell in place, a wire binding screw for said ring, a rotatable screw crown for the front end of said 95 body having an end contact and a wire binding screw, and provided with a wire-gripping portion extending into said central opening to co-operate with said gripping surfaces.
21. In an attachment plug for electric 100 wires, an open body having a screw shell rotatably mounted thereon, and a contact member for said shell at the front end of said body having a wire binding screw, in combination with a rotatable crown having a slotted edge and a non-conducting screw stem in separable engagement with said body and a central contact at the front of said crown comprising a wire-binding screw.
22. In an attachment plug for electric 110 wires, a body having a central screw-opening with side channels and wedging portions for the wires, a screw shell rotatably mounted upon the body, and a contact member for said shell having a wire-binding screw, in combination with a slotted crown having a screw stem to enter said screw opening in the body and wedge the wires therein, and an end contact and a wire-binding screw at the front of said crown.
23. In an attachment plug for electric 115 wires, a body and a screw shell rotatably mounted upon said body, said shell having an inturned flange at its front end, a contact ring inseparably united in rotatable engagement with said shell-flange and having a wire-binding screw, and an end contact and wire-binding screw carried by said body.

24. In an attachment plug for electric wires, a body having wire passages and a screw shell, a non-conducting crown in rotatable screw engagement with said body having a series of equi-distant radial slots extending inward from the edge thereof adapted to be alined with one of said passages, and separate wire-connecting terminals at the front ends of said body and crown, respectively.

In testimony whereof I affix my signature in presence of two witnesses.

WILLIAM C. TREGONING.
